DETACHABLE SCREEN FOR AUTOMOBILES

Gustav Roedel, Camden, N. J.

Application August 10, 1940, Serial No. 352,148

1 Claim. (Cl. 156—14)

The present invention relates to new and useful improvements in screens for the windows of automobiles and similar vehicles and has for its primary object to provide means for detachably supporting the frame of the screen in the frame of the window and also to provide a pivotal mounting for one end of the screen in order that the screen may be formed laterally outwardly from the window to enable the driver to give a desired hand signal.

A further object of the invention is to provide a detachable screen of this character of simple and practical construction, which is neat and attractive in appearance, relatively inexpensive to manufacture, easy to install in position in the window frame and otherwise well adapted for the purposes for which the same is intended.

Other objects and advantages reside in the details of construction and operation as more fully hereinafter described and claimed, reference being had to the accompanying drawing forming part hereof, wherein like numerals refer to like parts throughout and in which:

Figure 1 is a side elevational view of a window of an automobile showing the screen mounted in position therein.

Figure 2 is a sectional view taken substantially on the line 2—2 of Fig. 1.

Figure 3 is a fragmentary sectional view taken substantially on the line 3—3 of Fig. 1 and showing the snap catch for the screen.

Figure 4 is a fragmentary detail of the handle provided for the screen and

Figure 5 is a vertical sectional view taken substantially on the line 5—5 of Fig. 1.

Referring now to the drawing in detail wherein for the purpose of illustration I have disclosed a preferred embodiment of the invention the numeral 5 designates the screen frame which is preferably constructed of metal and having the channel 6 formed therein within which the wire screening 7 is secured by rivets or other fastening means 8.

Secured to the inner face of the screen 5 is a frame member 9 which is coextensive with the frame 5 and projects laterally from the screen frame 5 substantially in the form of a flange which extends entirely around the margin of the screen frame on the inner face thereof, as shown to advantage in Figs. 3 and 5 of the drawing.

The frames 5 and 9 are adapted to conformably fit within the window frame 10 of an automobile body outwardly of the window slot 11 formed therein.

Projecting from the upper edge of the frame 9 is a pin 12, the pin being positioned adjacent the rear edge of the frame and in vertical aline-

ment with the pin, the frame 9 is provided with an opening 13 within which a screw 14 is adjustably secured, the lower end of the screw projecting beneath the frame 9 and is provided with a reduced smooth extension 15. The pin 12 is adapted to be seated in a recess formed in the upper edge of the window frame 10 and the reduced smooth extension 15 of the screw 14 is adapted to be seated in a similar opening in the bottom edge of the window frame whereby to provide for the pivotal movement of the screen in the window frame.

The front edge of the frame 9 is provided with a spring projected catch 16 mounted in a housing 17 carried by the frame 9, the outer end of the catch being rounded as shown to advantage in Fig. 3 of the drawing and adapted to be seated in a shallow recess 18 formed in a plate 19 mounted in the front edge of the window frame 10 whereby to secure the screen frame in a closed position in the window opening.

Outward pressure exerted on the front portion of the screen will move the screen outwardly on the pivot pins 12 and 15 so that the hand of the driver may be extended from the window of the car to give the desired signal and to the inner sides of the frame 9, adjacent its front edge is secured a bracket 20 to which a knob 21 is secured for pulling the screen into its closed position.

It is believed the details of construction, advantages and manner of use of the device will be readily understood from the foregoing without further detailed explanation.

35 What is claimed is:

A window screen comprising a pair of inner and outer coextensive frames laterally secured together for conformably fitting within a window opening, screening material secured within the 40 confines of the outer frame, and said inner frame adjacent one end thereof having an integral up-standing pivot pin at the top side of said inner frame, and also having in the bottom side thereof and in substantial alignment with said integral 45 pivot pin a through threaded opening, a pivot screw having a threaded fit in said opening for coaction with said pivot pin and pin-accommodating openings in a window frame for pivotally mounting said screen within the window frame; 50 a spring-projected catch embodying a housing mounted in an end member of the inner frame, and an angular bracket secured to said end member of the inner frame at the side of said member remote from the outer frame and provided with a knob to facilitate manual swinging movement of said screen.

GUSTAV ROEDEL.
